UNITED STATES PATENT OFFICE.

WILLIAM C. MARTINEAU AND CLARENCE R. MARTINEAU, OF ALBANY, NEW YORK.

CAR-DOOR DEVICE.

1,170,656.

Specification of Letters Patent.

Patented Feb. 8, 1916.

Application filed April 3, 1915. Serial No. 19,021.

To all whom it may concern:

Be it known that we, WILLIAM C. MARTINEAU and CLARENCE R. MARTINEAU, both citizens of the United States, and residents of Albany, Albany county, New York, have invented certain new and useful Improvements in Car-Door Devices, of which the following is a specification.

Our invention relates to devices or appliances to be attached to freight car or other sliding doors for securing them in position and for providing means for sealing or locking them. Its object is to provide simple, cheap durable, easily securable and efficient means to these ends.

In the drawings, which represent a preferred form of our device, Figures 1 and 2 are respectively a top plan view and an elevation thereof; Fig. 3 is a partial inverted plan view; Fig. 4 is a vertical section through the plane 4—4, Fig. 2; Figs. 5 and 6 are perspective views of detached parts.

11 designates a car, having door opening 12, door 13 and stile 14. On door 13 is secured, as by bolts 15, the bolt or staple carrying portion 16 of the device comprising a body 17 and a strap end 18. Body 17 has a central arched member 19 between two flanges 20, member 19 having a transverse semi-circular depression 21. From lower flange 20 projects a raised lug 22, clearly shown in Fig. 3, having a vertically disposed member 23 pierced with an aperture 24. A strap portion 25 is superposed on body 17 and is formed with a semi-circular depression 26, complementary to depression 21 and with bolt apertures registering with those in flanges 20, see Fig. 4. On stile 14 is bolted a combined striker, 40 guide and bolt socket 27, shown detached in Fig. 5, having a striker flange 28 on the door side of the stile, a right-angled flange 29 at the opposite side and provided with a bolt hole 30, the member 31 connecting these flanges being extended to form a flange 32 having a rounded face 33 adapted to pass under arched member 19 and to engage over door 13 to guide it into position and prevent rattling of the door. On member 31 are two forwardly projecting members 34 and 35, member 34 being formed with a deep U-shaped depression or socket 36, and member 35 with a transverse aperture 37. A bolt 38, shown 55 detached in Fig. 6, comprises a cylindric body 39, having at one end a head 40, and

adjacent its other end an L-shaped engaging and locking portion comprising a laterally projecting stem 41 and a flat member or lug 42 apertured at 43 extending transversely from stem 41, i. e., substantially parallel with body 39.

The parts are assembled as shown in the drawings, it being seen that body 39 of bolt 38 is placed in depression 21 before portion 25 is superposed on body member 19, so that bolt body 39 has free movement in depressions 21 and 26, and the same bolts 15, see Fig. 3, pass through both flanges 20 and those in portion 25, so that this strap portion and bolt 38 are firmly secured to door 13.

The operation of the device is clearly shown in the drawings. Bolt 38 being turned so as to bring member 42 upward, as in dotted lines, Fig. 2, door 13 is forced against stile 14, flange 32 engaging over the edge of the door; the bolt is then moved to the left of Figs. 1, 2 and 3, so as to clear stem 41 from depression 36 and to bring the free end of body 39 into aperture 37. The bolt being given a semi-rotation to bring member 42 to its lowermost position, Figs. 2 and 3, the shackle of a seal or lock 44 is passed through apertures 43 in the bolt and 24 in member 23, thus preventing the return of member 42 to its upward position, which is necessary to the withdrawal of the bolt from member 34.

It is obvious that many mechanical alterations may be made in the device without departing from our invention, as e. g., a mere reversal of the relative position of the parts. It is also clear that the term "car door" has no especial significance, and is used to indicate any sliding door wherever used.

What we claim is:

1. A car door fixture for securing a sliding door to a stile or the like, comprising a bolt carrying portion secured to one of said car parts and formed with a laterally projecting lug having an aperture; a bolt having limited longitudinal and rotary movement in said carrying portion and formed with an L-shaped, engaging and locking member comprising a laterally projecting stem and a lug having an aperture and extending transversely from said stem; a socket portion on the other of said car parts adapted to receive said bolt and to permit the passage of said L-shaped member when said bolt has

been rotated to bring said member into one position and to prevent withdrawal of said bolt when it has been rotated to bring said member into another position; the construction of the parts being such that when said bolt has been rotated to its last-named position said lugs will be brought into substantial contact and the apertures therein into registration, whereby the shackle of a seal or lock may be passed through both said apertures.

2. A car door fixture for securing a sliding door to a stile or the like, comprising a bolt carrying portion secured to one of said car parts and formed with a laterally projecting lug having an aperture; a bolt having limited longitudinal and rotary movement in said carrying portion and formed with a laterally projecting member spaced away from its free end; a socket portion on the other of said car parts formed with a U-shaped member adapted to receive said bolt and to permit the passage of said lateral member when said bolt has been rotated to bring said member into one position and to prevent withdrawal of said bolt when it has been rotated to bring said member into another position, and with a second socket apertured to receive the free end of said bolt; said projecting member on said bolt being formed with an aperture adapted to register with the aperture in said lug when said bolt has been rotated to its last-named position, whereby the shackle of a seal or lock may be passed through both said apertures.

3. A car door fixture for securing a sliding door to a stile or the like, comprising a bolt carrying portion secured to one of said car parts and having an arch-shaped head spaced away from said car part; a horizontally disposed bolt having limited longitudinal and rotary motion in said head and formed with a laterally projecting member; a combined guide and socket portion on the other of said car parts having a member adapted to engage over the edge of the other car part beneath said arched head and a bolt receiving socket adapted to permit the passage of said bolt when it has been rotated to bring said projecting member into one position and to engage with said member after

said bolt has been rotated to bring said member into engaging position.

4. A car door fixture for securing a sliding door to a stile or the like, comprising a bolt carrying portion secured to one of said car parts and provided with a lug formed with an aperture therein and spaced away from said car part; a bolt having limited longitudinal and rotary movement in said carrying portion and formed with a laterally projecting member at the free end of which is a flange formed with an aperture therein; a combined striker, guide and socket portion on the other of said car parts having a member adapted to engage over the edge of said first named car part beneath said lug and adapted to permit the passage of said bolt and of said projecting member when said bolt has been rotated to bring said projecting member into one position and to engage with said member to prevent withdrawal of said bolt therefrom when it has been rotated to bring said apertures closely adjacent, whereby a shackle may be passed through both said apertures to prevent rotation of said bolt.

5. A car door fixture for securing a sliding door to a stile or the like, comprising a bolt carrying portion secured to one of said car parts and including an arch-shaped head spaced away from said car part and an independent, bolt-retaining strap member superposed on and bolted to said head; a bolt having limited longitudinal and rotary movement in said head and formed with a laterally projecting member; a combined guide and socket portion on the other of said car parts having a flange member adapted to engage over the edge of said first named car part beneath said arched head, and a bolt receiving socket adapted to permit the passage of said bolt when it has been rotated to bring said projecting member into one position and to engage with said member after said bolt has been rotated to bring said member into engaging position.

WILLIAM C. MARTINEAU.
CLARENCE R. MARTINEAU.
